UNITED STATES PATENT OFFICE.

RUDOLPH BECKER, OF ROSELLE PARK, NEW JERSEY, ASSIGNOR TO THE SINGER MANUFACTURING COMPANY, A CORPORATION OF NEW JERSEY.

FEEDING MECHANISM FOR SEWING-MACHINES.

1,397,071.

Specification of Letters Patent.

Patented Nov. 15, 1921.

Original application filed November 5, 1917, Serial No. 200,273. Divided and this application filed November 19, 1918. Serial No. 263,135.

To all whom it may concern:

Be it known that I, RUDOLPH BECKER, a citizen of the United States, residing at Roselle Park, in the county of Union and State of New Jersey, have invented certain new and useful Improvements in Feeding Mechanism for Sewing-Machines, of which the following is a specification, reference being had therein to the accompanying drawings.

This application is a division of my application Serial No. 200,273, filed November 5, 1917, and relates to the feeding mechanism for advancing the work a stitch length at a time.

It aims to provide a new and improved mechanism which is simple in construction and both durable and powerful in operation.

It also aims to provide a feed-regulator which is accessibly located at the front of the machine and conveniently operated.

The invention further aims to provide adjustments enabling the projection of its teeth above the plane of the throat-plate being nicely determined to suit the requirements of the different grades of straw braid the machine is designed to stitch together.

The feed-dog is adjustably supported on a lever which is actuated by a rocker from an eccentric on the main-shaft and thereby work-advancing movements are imparted to it. Vertical components of motion are imparted to the feed-dog from a substantially vertically arranged pitman embracing a second eccentric on the main-shaft. A link connects the lower end of the vertically arranged pitman with the lever on which the feed-dog is mounted being connected to the latter adjacent the feed-dog.

The invention is illustrated in the accompanying drawings, in which Figure 1 is a perspective of a straw-braid sewing machine to which the feeding mechanism has been applied. Fig. 2 is an end elevation of the machine with the overhanging bracket-arm omitted. Fig. 3 is a perspective view of the feed-dog mounted on the lever which carries it. Fig. 4 is a vertical transverse section showing the feed-regulating lever. Fig. 5 is a rear side elevation, partly in section, showing the location of the vertically arranged lifting pitman and Fig. 6 is a detail in perspective of the vertically arranged lifting pitman and a link actuated thereby.

Fig. 7 is a detail of a segment plate for gaging the feed regulator.

The machine in which the invention has been incorporated is provided with the usual overhanging bracket-arm 1 supported at one end by a vertical standard 2 rising from a base 3. Suitably journaled in the frame of the machine is a main-shaft 4 which is driven through a belt-wheel 5 on one end thereof, the opposite end of the main-shaft terminating substantially flush with the opposite exterior face of the frame of the machine.

The stitch-forming mechanism comprises a hooked needle 6, an eye-pointed needle 7 actuated from below the throat-plate 8 and coöperating with the needles above the presser-foot 9 are a pair of angularly disposed loopers 10 all of the form and arrangement shown in my parent application above mentioned and all actuated by mechanism such as is therein fully disclosed.

The feed-dog 11 is cut away at one corner to clear the needles 6 and 7, see Figs. 2 and 3. Its usual serrated upper face is gouged out in the line of seam-formation directly in rear of the needles alongside of which stand prongs 12 insuring against slippage of the work during the step-by-step advance thereof. A depending post 13 integral with the dog is fixed by a screw 14 between the flanges 15 on a block 16 which is clamped by a screw 17 in the channeled head 18 of a feed-dog supporting member in the form of a link 19 with an enlarged and offset portion at one end constituting the above mentioned head 18. To permit adjustment of the feed-dog relative to the channeled head 18, see Fig. 2, the block 16 is slotted as indicated at 20 to receive the clamping screw 17. For effecting a nice or minute adjustment of the feed-dog relative to its support and to thus determine its maximum projection through and above the throat-plate, a turn-screw 22 is threaded into the block 16 and its restraining collar 23 is rotatably mounted in the slots 24 of the channeled head 18.

The feed-dog is moved in an elliptical path, the resultant of combined horizontal and vertical components of motion and characteristic of four-motion feeding mechanisms.

For lifting the feed-dog the eccentric 25,

indicated in dotted lines in Fig. 2 is embraced by a pitman 26 extending downwardly and laterally a relatively considerable distance, in the present instance about 5 two and three-fourths inches, in between the sides of a groove 27 in the disk-like head 28 of a swivel-pin 29 (Fig. 6 only) mounted in the frame where the pitman is provided with a pivotal connection 30 to an upwardly extending link 31 bent intermediate its ends as shown at 32 in a direction away from the pitman 26 and extending upwardly to its point of pivotal connection with the feed-dog supporting member. The pivotal connection 10 between the link and the feed-dog supporting member is in the form of a relatively long pin 33, set-screwed as indicated at 34 fast to the link 31 and having a head 35 at its opposite end restraining endwise 15 movement of the boss 36 of the feed-dog supporting member 19 embracing the pin. The upper end of the link 31 above the bend 32 is steadied between a vertical face of the lug 37 integral with the frame and a 20 25 U-shaped plate 38 screwed thereto as shown. The feed-dog is given its vertical components of motion or lifting movements through these connections.

For imparting feeding movements to the dog the eccentric 39, Fig. 4 on the main-shaft is embraced by a pitman 40 extending rearwardly a relatively considerable distance, in the present instance about 4 inches, where a block 41 is pivoted so as to slide in 30 35 an arcuate slot 42 in a feed rocker 43 pivoted at its lower end to the frame of the machine as shown at 44. At the upper end of the rocker the feed-dog supporting member or link 19, is pivoted on the pin 45. At the 40 front end of the link 19 the before mentioned boss 36 extends laterally into proximity with the feed-dog where the channeled head 18, adjustably supporting the feed-dog, is located. Through these 45 50 connections the feed-dog is given its horizontal components of motion or feeding movements which it is to be observed are substantially flat because of the relative great length of the vertically arranged link 31 carrying the pin 33 or movable fulcrum of the feed-dog supporting member.

A feed regulator is provided for varying the length of stitch, such variations occurring at the rear end of the feed-stroke being 55 cause the center of curvature of the slot 42 in the rocker 43 coincides with the center of the feed eccentric 39 when the same is at its most forward position and consequently the feed-dog always rises and engages the work 60 at the same point relative to the paths of the needles. The feed regulator is in the form of a lever 46, Fig. 4 pivoted on the main-shaft 4 between collar 47, Fig. 1 and the feed-eccentric 39 and having a fork 48 65 curved as shown at the end of its long arm

embracing a friction roll 49 carried by the block 41 in the slotted feed-rocker 43 so that the operator is enabled on manipulating the opposite end of the lever to shift the block to and from the fulcrum of the feed-rocker 70 to vary the length of feed or stitch. Convenient control of the feed regulator is provided by extending a rod 50, Fig. 4 secured in the short arm 51 of the lever through a slot 52 in the front wall of the frame in 75 register with which slot is a correspondingly shaped opening in a segment plate 53 secured by screws 54, to the frame and provided on opposite sides of the elongated opening with a series of sockets 55, Fig. 7. 80 A handle 56 is sleeved on the end of the rod 50 and a coiled spring 57 is interposed between the bottom of the socket in the handle and the head of a screw 58 threaded into the rod 50. A pair of diametrically disposed pins 59 are arranged on the inner end of the handle 56 and are adapted to seat in the sockets 55 in the plate. These sockets and pins may be of such size, shape and spacing as to permit of any desired variations in the length of stitch. 90

Having thus set forth the nature of the invention, what I claim herein is:—

1. In a feeding mechanism for sewing machines, a feed-dog, a main-shaft, means for imparting feeding and lifting movements to said feed-dog including a feed-rocker provided with a slot and pivoted a substantial distance in rear of the main-shaft, a slide-block fitted to the slot in said feed-rocker, 95 an eccentric element on said shaft, a strap connecting said eccentric element and said slide-block, and a lever pivoted on said shaft for adjusting said slide-block in said slot, a segment-plate having a series of sockets 100 located at the front of the machine, an operating handle on said lever, and one or more yieldingly supported detent-pins on said handle adapted to seat in said sockets and hold said lever in an adjusted position. 110

2. In a feeding mechanism for sewing machines, a feed-dog, a feed-dog supporting member, a main-shaft, mechanism for imparting feeding movements to the dog, and mechanism for imparting lifting movements 115 to the dog including an eccentric element on said main-shaft, a grooved member swiveled in a fixed part of the machine and spaced a substantial distance below said main-shaft, a strap operated by said eccentric element at one end and at its opposite free end fitted to the groove in said member, a pin arranged in the free end of said strap, and a link connected to said pin and to said feed-dog supporting member adjacent the 120 feed-dog. 125

3. A feeding mechanism for sewing machines comprising a feed-dog, a feed-dog supporting member, means for imparting feeding movements to the dog and means 130

for imparting lifting movements to the dog including a swivel-pin provided with a guide, a driving member coöperating with the guide and guided thereby, a pivot-pin 5 carried by said driving member, and a link connecting said pivot pin to said feed-dog supporting member.

4. In a feeding mechanism for sewing machines, a feed-dog, a feed-dog carrying link 10 having an offset head, said dog being supported by said offset head, means for imparting feeding movements to the dog, and means for imparting lifting movements to the dog including a pitman, and a link, said 15 link and pitman being pivotally connected together at one end and offset laterally at their other ends.

5. In a feeding mechanism for sewing machines, a feed-dog, a feed-dog carrying link 20 having an offset head, said dog being supported by said offset head, means for imparting feeding movements to the dog, and means for imparting lifting movements to the dog including a pitman, and a link, said 25 link and pitman being pivotally connected together at one end and offset laterally at their other ends.

the dog including a pitman and a link, said link and pitman being pivotally connected 25 together at one end and offset laterally of their other ends, and means for steadyng the offset portion of the link against displacement or flexure in a direction trans- 30 verse the direction of feed.

6. In feeding mechanism for sewing machines, a feed-dog, a feed-dog supporting member, a shaft, means for imparting feeding movements to the dog, and means for imparting lifting movements to the dog comprising 35 a driving element on the shaft, a swiveled guide member, a driving means leading from the driving element to the guide member, and guided thereby, and a link having pivotal connection with said 40 driving means and connected to the feed-dog supporting member.

In testimony whereof, I have signed my name to this specification.

RUDOLPH BECKER.
